UNITED STATES PATENT OFFICE.

KARL WITTIG AND EMIL WITTIG, OF ZELL, WIESENTHAL, GERMANY.

ROTARY ENGINE.

985,091.

Specification of Letters Patent. Patented Feb. 21, 1911.

Application filed April 4, 1910. Serial No. 553,239.

To all whom it may concern:

Be it known that we, KARL WITTIG and EMIL WITTIG, the first a subject of the Grand Duke of Baden and the second a subject of the King of Saxony, both residents of Zell, in Wiesenthal, in the Grand Duchy of Baden, Germany, have invented new and useful Improvements in Rotary Engines, of which the following is a full and exact specification.

The invention relates to improvements in rotary engines, which may be utilized as motors, pumps, ventilators and compressors and which are of the kind having a crescent shaped working chamber divided into a certain number of cells by radially movable pistons carried by a cylindrical drum eccentrically mounted in a cylindrical casing. In order to counteract the centrifugal forces of the pistons in such engines and at the same time reduce the friction to a minimum, it has already been proposed to provide one or more revoluble supporting rings which serve to prevent the outer ends of the pistons coming into contact with the stationary cylinder and thus take up the centrifugal forces of the pistons.

Now, the present invention relates to improvements in rotary engines and the like with revoluble supporting rings of this kind, wherein each of the supporting rings of an internal diameter corresponding to, or approximately corresponding to the diameter of the cylinder bore, is located in a groove in the cylinder wall with a certain amount of play in planes at right angle to the axis of the engine shaft. But since, the pressure existent within the engine tends to displace the revoluble supporting rings radially with considerable force, each of the supporting rings is, according to the present invention, provided with partitions extending in the direction of the axis and fitted to the outer surfaces of the revoluble supporting ring, the said partitions yieldingly bearing against the fixed casing and forming thereby revolving chambers, which are connected with the interior of the engine and in which the pressure fluid is admitted, in order to counterbalance the inner radial pressure, the intensity of the fluid pressure and the size of the said pressure counterbalancing chambers determining the degree of the counterbalancing effect. In order, in a rotary engine of this kind, to maintain the re-

quired tightness at the end faces against which the revoluble parts turn, notwithstanding the differences in expansion of the revoluble parts (pistons carrier and pistons) and the fixed casing, an end wall of the casing is made movable relatively to the revoluble parts and subjected to the action of a pressure device, in such a manner that the contacting surfaces of the said revoluble parts and of the said end wall running on each other, are pressed against each other and that, when the friction between the end wall and the revoluble parts becomes too great, the said end wall and revoluble parts move together to a slight extent and slacken thereby somewhat the pressure device. In order, furthermore, to produce the compensation effect already known in connection with air pumps having reciprocating pistons (communication between both cylinder ends for a short time at each dead point position of the piston), in a rotary engine of this kind, which is to be used as an air or gas pump, the engine is provided with connecting channels which serve as connection between the working cells, which have just expelled their contents and those which have completed their suction action.

To enable our invention to be fully understood we will describe the same by reference to the accompanying drawings, in which

Figure 1 illustrates a section on the line z, z , of Fig. 2 of a rotary engine constructed in accordance with our invention. Fig. 2 is a vertical section of the same on the line y, y of Fig. 1. Fig. 3 an end view, partly in section on the line z, z of Fig. 1, and Figs. 4, 5 and 6 show modifications of parts of the engine.

In the construction shown in Figs. 1, 2 and 3, a piston carrier or drum 1 is eccentrically mounted in the cylindrical casing 2. The crescent-shaped working chamber is divided into cells by a number of pistons 3 which may be made of thin hardened steel plates. Two supporting rings 4 which revolve with the said pistons 3, and take up the centrifugal forces of the same practically without friction, have an inner diameter, which is the same as that of the cylinder chamber 2, and are inserted in grooves 5, so that they can move quite freely perpendicularly to the longitudinal axis of the cylinder chamber, and can freely adjust themselves to the outer piston ends and so

make sure of the pistons 3 contacting equally well with the supporting rings 4 and with the cylinder wall.

By arranging the supporting rings in 5 grooves in the cylinder wall and giving them radial play, as described, the annular space behind each ring 4 may be used for the purpose of counterbalancing the inner radial pressure on the rings 4. Such 10 a counterbalancing effect is attained by fitting the exterior of the supporting rings 4 with partitions 6 which extend in the direction of the axis, and yieldingly contact with the casing, thus providing 15 limited revolving pressure counterbalancing chambers around the rings 4. These chambers are directly connected with the interior of the engine by means of channels 7 formed by simple borings which convey 20 the pressure. The partitions 6 are simply inserted into grooves in the rings 4 and are pressed close against the housing by the centrifugal force which renders springs and the like unnecessary for this purpose. 25 The partitions 6 and channels 7, which revolve with the rings 4, act on the oil like centrifugal pumps and continually press the same behind the rings 4 so that these always run in oil.

30 Although it may appear to be best to connect each pressure chamber with the point of the interior of the machine situated directly radially opposite to its middle part this is not always so, since there are forces 35 in addition to the radial pressure acting on the rings 4. For example, when the engine is used as an air pump, there is considerable friction between the pistons and their guides on that side of the engine on which compression takes place, and as a result the pistons press more strongly outward on to the rings 4 on this side than on the other side, and consequently an increased counterbalancing 40 action of the rings 4 from the inner pressure 45 is required on the compression side. This increased counterbalancing action may be effected by connecting the pressure counterbalancing chambers with points of the interior of the engine which are in advance 50 relatively to the direction of rotation, since the internal pressure increases on the compression side in the direction of rotation. This particular construction is illustrated at the upper part of Fig. 2, where it will be 55 seen that the part 7 runs obliquely through the supporting ring. In rotary motive power engines (motors on the other hand, the conditions are reversed), a weakened counterbalancing action being necessary, 60 which also is attained by forward displacement of the channel 7 in the direction in which the volume of the cells increases.

It will be understood that the channels 7 65 may be fitted in the fixed instead of the revolving part.

To insure the automatic tightness at the end walls of the cylinder as described above, the left end plate 9 of the casing 2 is movably and revolvably arranged and carries a screw-threaded boss 8 which engages a fixed female screw 10 in the casing 2. The disk 9 is subjected to a turning moment (rotation moment) in a direction contrary to that of the rotation of the engine, either by means of a weight 11 suspended from the boss 8, or by other suitable means. The cut of the screw-thread on the boss 8 is so made that in consequence of the turning moment the disk 9 is moved toward the piston carrier 1 until it touches the same. If now the friction moment between the piston drum 1 and disk 9 is greater than the turning moment exercised by the weight 11, the disk 9 will be carried along slightly by the piston drum 1, and will then move away owing to its guidance by a screw thread until the friction moment and the turning moment are equal. In other words the amount of the friction moment can be regulated by regulating the amount of the turning moment.

To effect the pressure compensation previously referred to, a channel 12 situated at a convenient point, as near as possible to the cell having the smallest volume, between the suction and expulsion ports, extends into the interior of the cylinder. One end of a pipe 13 is attached to the said channel 12 and the other end to a channel 14 which also leads into the interior of the cylinder at 95 a point behind the suction port in the direction of rotation. In this manner, connection is established between the cells 15 which have just expelled their contents and contain air at the expulsion pressure and cells 16, wherein there exists a pressure which is only slightly greater than the suction pressure. In other words, a flow of air from the cells 15 into the cells 16 will take place, wherever there is a difference in pressure 105 between the two cells. The pipe 13, for which may be substituted a connection channel in the cylinder wall, is conveniently provided with a cock 17 to enable the pressure compensation to be regulated as desired. A 115 number of such conduits 12, 13 and 14 may be provided so that each cell 15 after having left the expulsion channel will first be connected with a cell 16 in which a moderate compression has already taken place, and 120 so that on further rotation the said cell 15 will be connected with a cell 16 which is further behind in the direction of rotation, that is to say, contains air at a lower compression. In this manner the pressure compensation becomes more steady.

In order that the pistons 3 shall bear against the cylinder wall with safety particularly when starting the machine, they may be connected by tension devices with 130

the rings 4, as for example, shown in Fig. 6, in which a dove-tailed groove in the ring 4 is engaged by a corresponding projection on the piston.

Instead of screw-threading the disk 9 other means may be provided, which during the rotation of the said disk effect its displacement in the direction of the axis. In Fig. 4 the disk 9' bears against a rigid support 18 through the medium of levers 17 which are inclined to the direction of the axis and, owing to the turning moment generated by the weight 11, tend to right themselves and displace the disk 9 against the piston drum 1. The method of adjusting the proper pressure is then practically the same as when using a screw-thread, provided the movements of the levers 17 are not too great.

If the position of the resultant force of all the forces which tend to press the disk 9 outward is known, a single roller which bears against a short portion of a screw thread may be employed, as it is shown in Fig. 5, wherein the disk 9'' carries at the proper point the inclined surface 19 which during the rotation of the disk 9 under the influence of the weight 11 presses against the roller 21 carried by a fixed support and thereby move the disk inward.

What is claimed is:

1. In an apparatus of the character described, a cylinder having at least one circumferential groove in the interior wall thereof, a drum eccentrically mounted in said cylinder, a plurality of pistons upon said drum and movable radially thereof, at least one supporting ring of approximately the same internal diameter as the cylinder-bore, located in said groove in the cylinder and having play perpendicular to the longitudinal axis of the cylinder, the said supporting ring revolving with the said pistons and being designed to take up the centrifugal force thereof, partitions on the exterior of the supporting ring, yieldingly contacting with the bottom of said groove, and passages from the interior of the cylinder to the exterior of said ring between partitions, the said partitions forming chambers wherein fluid pressure may be admitted from the interior of the cylinder through the said passages to counterbalance the pressure on the interior face of said supporting ring.

2. In an apparatus of the character described, a cylinder having at least one circumferential groove in the interior wall thereof, a drum eccentrically mounted in said cylinder, a plurality of pistons upon said drum and movable radially thereof, at least one supporting ring of approximately the same internal diameter as the cylinder-bore, located in said groove in the cylinder and having play perpendicular to the longitudinal axis of the cylinder, the said sup-

porting ring revolving with the pistons and being designed to take up the centrifugal force thereof, longitudinal grooves in the exterior sides of the supporting ring, partitions movably fitting in said longitudinal grooves and projecting into contact with the bottom of the circumferential groove in said cylinder when said ring is acted upon by centrifugal force, and passages from the interior of the cylinder to the exterior of said ring between partitions, the said partitions forming chambers wherein fluid pressure may be admitted from the interior of the cylinder through the said passages to counterbalance the pressure on the interior face of said supporting ring.

3. In an apparatus of the character described, a cylinder having at least one circumferential groove in the interior wall thereof, a drum eccentrically mounted in said cylinder, a plurality of pistons upon said drum and movable radially thereof, at least one supporting ring of approximately the same internal diameter as the cylinder-bore, located in said groove in the cylinder and connected with the pistons by means of tension devices insuring the contact between them, the said supporting ring revolving with the said pistons and designed to take up the centrifugal force thereof, partitions on the exterior of the supporting ring, yieldingly contacting with the bottom of said groove, and passages from the interior of the cylinder to the exterior of said ring between partitions, the said partitions forming chambers wherein fluid pressure may be admitted from the interior of the cylinder through the said passages to counterbalance the pressure on the interior face of said supporting ring.

4. In an apparatus of the character described, a cylinder, a rotary element within said cylinder, a longitudinally movable and revolvably arranged cylinder end wall, and means pressing said end wall into contact with said rotary element but yieldable under an increase of friction to decrease the contact between said parts.

5. In an apparatus of the character described, a cylinder, a rotary element within said cylinder, a longitudinally movable and revolvably arranged cylinder end wall, means pressing said end wall into contact with said rotary element by a turning moment exercised on the said wall in a direction contrary to that of the rotation of the rotary element and means causing the said end wall to move longitudinally away from the said rotary element, when the moment of friction between them is greater than the turning moment exercised on the end wall to decrease the contact between the latter and the rotary element.

6. In an apparatus of the character described, the combination of a cylinder hav-

1
ing circumferential grooves in the interior wall thereof, a drum eccentrically mounted in said cylinder, a plurality of pistons upon said drum and movable radially thereof,
5 supporting rings of approximately the same internal diameter as the cylinder-bore, located in said grooves in the cylinder and having play perpendicular to the longitudinal axis of the cylinder, and means connect-
10 ing said pistons to said rings, whereby the outer ends of the radial pistons may bear tightly but with different degrees of pressure against both the cylinder and the sup-

porting rings when the drum is rotated, the supporting rings revolving with the pistons 15 and counteracting the centrifugal force thereof.

In witness whereof we have hereunto signed our names this 24th day of March 1910, in the presence of two subscribing witnesses.
